FOREST YOCKEY AND CHARLES D. MCLEOD, OF SIOUX CITY, IOWA.

SAFETY GAS-VALVE.

No. 885,136.

Specification of Letters Patent.

Patented Aug. 4, 1908.

Application filed March 10, 1908. Serial No. 420,175.

To all whom it may concern:

Be it known that we, FOREST YOCKEY and CHARLES D. MCLEOD, citizens of the United States, residing at Sioux City, in the county of Woodbury and State of Iowa, have invented new and useful Improvements in Safety Gas-Valves, of which the following is a specification.

Our invention relates to gas fixtures and 10 burners and has for its object the provision of means for making the use of gas safe and free from accident.

The invention consists of the parts herein-after specified and in the arrangement and 15 combination of those parts as will be described and pointed out in the claims.

It is well known that many accidents and 20 deaths result from ignorance and carelessness in the adjustment of gas burners and in blowing out the light without stopping the flow of gas. Our invention makes it impossible for the gas to flow after the light is extinguished, as putting out the light automatically closes the gas cock. This is accomplished by the 25 devices shown in the accompanying drawing in which

Figure 1 is a longitudinal section of gas fixture showing the bracket, arm and burner. Fig. 2 is a plan view of lever used in closing 30 the valve. Fig. 3 is a vertical section of gas burner or lamp and section of nipple. Fig. 4 is a cross-section of gas burner on line X-Y, Fig. 3.

In the drawing A is a gas bracket attached 35 to a section of gas pipe B.

C is a movable, hollow arm pivotally secured to the bracket having at its opposite end a seat D terminating in a threaded nipple E.

40 So far the construction is the same as the ordinary gas fixtures except that the entrance to the hollow arm is through the top of the bracket by means of the opening a' leading from the usual duct a. The upper 45 part of the opening is in the form of a seat to receive a vertical valve b having an upper stem or guide c and lower stem d. Immediately above the valve in the cap of the bracket is a round slot or recess e, slightly 50 larger and shorter than the valve stem into which the stem is guided. In the lower part of the bracket is a rod f working in a slot in the lower part of the bracket directly in line with the valve stems. At the upper end it is 55 enlarged into a valve f' and at the lower end is a head g. Between the head and the

bracket a spiral spring h is coiled about the rod to normally hold the valve in its seat.

A curved pillar F, threaded in the usual manner, is attached to the nipple. In the 60 top of the shoulder F' of the pillar is a threaded opening into which is screwed the lower end of a threaded tube G, made preferably of copper or other expansive material. The upper end of the tube is internally threaded to receive a threaded plug H, of similar material. The plug has a central opening through which is inserted a wire I, made of hardened steel or other material little affected by heat and cold. The upper end of the wire forms a 65 knot or bulb i to prevent drawing through the plug. The lower end of the wire is secured to a lever J pivotally secured in the seat D at the outer end of the arm by means of a pin j passing through the lever and the 70 seat. The lever is preferably made of aluminum or any material which combines lightness with strength. It extends to the opposite end of the arm, tapering gradually to the end, where it is flattened to form a 75 hammer to strike the valve stem d. The wire is secured to the lever near the pivoted end of the latter, a slot k being made in one side of the lever in which the wire is adjusted, a bulb l in the end of the wire preventing the 80 wire from drawing through. The lower part of slot is enlarged to receive the bulb and leave the surface of the lever free.

It will be seen that the valve regulating the 85 supply of gas is controlled by the expansiveness of the tube G. When heat is applied by any means to the tube, the latter expands and lengthens, lifting the wire, which raises the free end of the lever, raising the valve b from its seat and letting in a supply of gas. 90 The jet may then be lighted. Or, the valve may be raised by pressing the head of the rod f. When the valve is raised and the gas lighted the lever will hold the valve free from its seat.

When the gas light is extinguished and the tube cools it contracts and shortens sufficiently to lower the wire and permit the free end of the lever to drop. The pressure of gas added to the weight of the valve will 105 close the valve and effectually shut off the supply of gas.

In Fig. 3 is shown a gas burner used in connection with our device, and forms one of the features of our invention. A pillar or burner 110 L is attached to the nipple and has a central opening m from one side of which leads

a duct *n*. The supply of gas in the duct is controlled by a needle valve or screw *M* entering from one side of the burner. Above the burner is the mixer of gas and air, consisting of two parts, a base *N* and cap *O*. In the center of the base is a threaded opening and in the under side is a circular groove *o*. Opening from the groove upward through the base are three outlets *p*, for the gas. The lower end of the tube *G* is adjusted to the central opening of the base. The upper rim of the burner and the outer rim of the base are threaded, while the lower part of the cap *O* is threaded internally and fits over them both, securing them firmly together. The base is thinner at the outer edge than in the center and forms a perfectly tight joint in the center when the cap is screwed down, preventing any flow of gas upward except through the outlets *p*. The cap or upper part of the mixer has four lateral openings *P* for the inlet of air which mixes with the upward flow of gas. The simplicity and utility of this form of lamp, and its use with the automatic valve, is one of the novel features of our invention.

Our device may be used either with or without the usual valve in the gas pipe.

The frame for the support of a glass chimney may be placed over the cap which is of usual shape and adapted to hold the frame.

Having described our invention, what we claim as new and desire to secure by Letters Patent, is—

- 35 1. In an automatic cut-off for gas burners, a valve in the arm of a gas fixture for regulating the flow of gas, a lever pivoted in said arm opposite said valve, the free end of said lever being adapted for contact with said valve, a piece of expansive material affected by heat and cold attached to said arm, pivotal connection between said piece and the free end of said lever whereby the lever is moved to open said valve when heat is applied to said piece and said piece expanded, and means connected with said valve for closing the same when the heat is withdrawn and said piece cooled, as and for the purposes specified.
- 50 2. In an automatic cut-off for gas burners, a vertical valve in the arm of a gas fixture for regulating the flow of gas, a lever pivoted opposite said valve, the free end of said lever having contact with said valve and adapted to lift the same from its seat, a piece of expansive material affected by heat and cold attached to said arm, pivotal connection between said piece and the free end of said lever whereby the lever is raised to lift said valve by the expansion of said piece when heat is applied and lowered to permit the closing of said valve when heat is withdrawn and said piece cooled, as and for the purposes specified.

3. A valve in the arm of a gas fixture for regulating the flow of gas, a pivoted lever controlling said valve, a tube of expansive material affected by heat and cold connecting with said arm, a wire connecting said tube with the free end of said lever whereby said lever is controlled by the expansion and contraction of said tube when heat is applied or withdrawn, and means for independently controlling said valve, as and for the purposes specified. 75

4. A valve in the arm of a gas fixture for regulating the flow of gas, a lever in said arm pivoted in the outer end thereof and adapted to control said valve, a tube of expansive material affected by heat and cold connecting with the outer end of said arm, a plug in the outer end of said tube, a wire connecting said plug with the free end of said lever whereby said lever is controlled by the expansion and contraction of said tube when heat is applied and withdrawn, as and for the purposes specified. 80

5. A valve in the arm of a gas fixture for regulating the flow of gas, a pivoted lever in said arm for controlling said valve, an upright pillar having a central opening from one side of which leads a duct for the escape of gas, connecting with the outer end of said arm, a valve in said duct for regulating the supply of gas, a mixer consisting of a base and cap secured to said pillar, said base having a central opening, and a circular groove on the under side thereof connecting with said duct, outlets in said groove for the escape of gas, said cap having lateral openings for the inlet of air, a tube of expansive material affected by heat and cold secured in the central opening of said base, a plug in the outer end of said tube and a wire connecting said plug with said lever whereby said lever is controlled by the expansion and contraction of said tube when heat is applied and withdrawn, as and for the purposes specified. 95

6. A valve in the arm of a gas fixture for regulating the flow of gas, a pivoted lever controlling said valve, an upright curved pillar secured to the outer end of said arm, a piece of expansive material affected by heat and cold secured to the shoulder or offset of said pillar, a wire connecting said piece with the free end of said lever whereby said lever is controlled by the expansion and contraction of said piece when heat is applied or withdrawn, as and for the purposes specified. 100

In testimony whereof we have signed our names to this specification in the presence of two subscribing witnesses.
